US00D645901S

(12) United States Design Patent
Csokmay

(10) Patent No.: US D645,901 S
(45) Date of Patent: * Sep. 27, 2011

(54) PEN

(75) Inventor: Joseph Csokmay, Parma, OH (US)

(73) Assignee: The Berea Hardwoods Co., Inc.,
Middleburg Heights, OH (US)

() Term: 14 Years

(21) Appl. No.: 29/374,136

(22) Filed: Jul. 7, 2011

(51) LOC (9) Cl. 19-06

(52) U.S. Cl. D19/55

(58) Field of Classification Search D19/35,
D19/36, 41-51, 54-58; 24/11 R, 11 P, 11 F;
401/52, 99, 100, 104-109, 192, 195, 196;
D14/411

See application file for complete search history.

Primary Examiner — Elizabeth Albert

(74) Attorney, Agent, or Firm — Baker & Hostetler LLP

(57) CLAIM

The ornamental design for a pen, as shown and described.

DESCRIPTION

FIG. 1 is a perspective view of a pen, showing my new design;
FIG. 2 is a front elevation view thereof;
FIG. 3 is a rear elevation view thereof;
FIG. 4 is a right elevation view thereof;
FIG. 5 is a left elevation view thereof;
FIG. 6 is a top view thereof; and,
FIG. 7 is a bottom view thereof.

The broken lines showing the barrel and clip of the pen in FIGS. 1-7 are included for the purpose of illustrating portions that form no part of the claimed design.

1 Claim, 2 Drawing Sheets
